UNITED STATES PATENT OFFICE

CHARLES H. KIRCOAF, OF PHILADELPHIA, PENNSYLVANIA, ASSIGNOR, BY MESNE ASSIGNMENTS, TO THE LANG COMPANY, OF GLOUCESTER, NEW JERSEY, A CORPORATION OF NEW JERSEY

BEATING APPARATUS

Application filed May 17, 1924. Serial No. 713,931.

My invention relates to beating engines utilized in beating or subdividing materials, such as rags, paper and the like, for producing pulp or stock utilized for manufacturing 5 paper and the like.

In accordance with my invention there is disposed in suitable position or relation with respect to the beater wheel or roll, preferably at or adjacent the highest portion of the backfall, a control member, preferably pivoted, adjustable toward and away from the wheel or roll, for graduating or varying the amount or proportion of the material operated upon which shall pass over the backfall for re-circulation to the beating mechanism, for graduating or varying the amount or proportion of the material which adheres to the beater roll or wheel and is carried thereby to suitable mechanism for removing the material and 10 discharging it from the engine, and for effecting a selective separation of the coarser and finer material from each other, the latter continuing with the beater roll or wheel and the former passing over the backfall and re-circulating to the beating mechanism.

Further in accordance with my invention the material operated upon passes, preferably continuously, from one beating engine to another of a series, whereby the material 15 is increased in fineness of subdivision in the successive engines of the series and finally discharged in suitable state of fineness, the operation by the beating engines in succession making possible a continuous treatment or 20 operation.

My invention resides in a method and apparatus of the character hereinafter described and claimed.

For an understanding of my method and 25 for an illustration of one of the various forms my apparatus may take reference is to be had to the accompanying drawing in which:

Fig. 1 is a plan view of a series of beating engines in accordance with my invention.

Fig. 2 is a vertical sectional view, partly 30 in elevation, on enlarged scale, on the line 2-2 of Fig. 1.

Fig. 3 is a fragmentary vertical sectional view, partly in elevation, taken on the line 35 3-3 of Fig. 1.

Referring to the drawing, each beater engine E comprises a tub 1 having a bottom 2 forming the trough 3 forming a complete circulatory system around the midfeather 4. In the bottom 2 is disposed the box 5 containing 55 the bed plates 6 adjacent which rotates the roll, drum or wheel 7 provided with the bars or spindles 8 and carried and driven by the rotating power shaft 9. Disposed above and enclosing the roll 7 is the cap 10 which may 60 carry the inwardly and outwardly adjustable blade or plate 11. Adjacent the roll 7 is the backfall 12 over which some of the material operated upon passes, flowing downwardly along the inclined bottom of the trough 3 in 65 re-circulation to the beating mechanism. The apparatus thus far described is a well known type of beating engine and is not perse my invention.

Secured upon the pivotal shaft 13, disposed 70 parallel with the axis of rotation of the roll 7, is the control plate or member 14 extending longitudinally of the roll 7 and adjustable toward and away from the roll by the operator's lever 15 secured upon the shaft 13 on the exterior of the engine. The member 14 is preferably pivoted at or adjacent the upper edge or highest portion of the backfall 12, as indicated. The direction of rotation of the drum 7 is indicated by the arrow, Fig. 2, and the 80 plate or member 14 is so pivoted that the drum rotates away from the outer or free end of the member 14.

The cap 10 has a portion 16 extending over the channel or trough 17, of width substantially equal to the width of the roll 7, and having the bottom board or member 18 with its inner end presented to the roll 7 and adjustable to different distances inwardly toward or outwardly from the roll 7, for removing stock or pulp from the roll and delivering it through the channel 17 into the trough or channel 19 extending above or common to the series of engines E. The channel 19 is provided, substantially in alignment 85 with the channel 17, with bottom slide 20 for opening or closing the pulp discharge aperture 21 through which all or a desired portion of the stock or pulp removed from 90 95 100

the roll 7 will be returned into the circulating trough 3 of the tub 1.

The channel or trough 19 is provided with a second slide 22 controlling a pulp discharge aperture 23 disposed over the trough 3 of each engine E.

The trough or channel 19 is inclined, as indicated in Fig. 3, from right toward the left, to a sufficient degree to effect flow of the stock or pulp delivered thereto.

Considering the operation of a single engine unit E, the stock or material flows in the trough 3 to the region of co-action of the roll 7 and the bed plates 6 where the material is ground, shredded or otherwise sub-divided and is carried around with the roll 7, in the direction of the extent of the control member 14 from its pivot 13, some of the material passing over the edge of the member 14 to the backfall 12 and thence into the trough 3 for re-circulation and re-treatment. The member 11, which may be omitted, serves to direct a portion of the material over the backfall into the re-circulating trough. The pulp or stock adhering to the roll is to suitable extent removed by the member 18, flows outwardly through the passage 17 into the trough 19 where, if the slide 20 has been removed from the opening 21, it again drops into the trough 3 and is recirculated for further grinding or treatment.

The position of the member 14 with respect to the roll 7 determines the proportion of the material which will adhere to the roll 7 and pass therewith to the member 18, and accordingly the position of the member 14 determines the proportion of the material passing the bed plates 6 with the roll 7 which will pass over the backfall and be re-circulated in the trough 3. As the outer end of the member 14 is adjusted closer to the periphery of the roll 7 more stock is carried around the roll and delivered by the member 18 through the passage 17 to the trough 19, and less passes over the backfall and is recirculated through the trough 3. Vice versa, as the upper end of the member 14 is adjusted away from the roll 7 more material is recirculated. Furthermore there passes around the roll 7 both coarse and fine material, the latter suitable for discharge from the engine unit and the former requiring further beating or grinding. The position of the control member 14 effects a selection as between fine and coarse material, the fine material adhering to the roll and passing therewith to the takeoff member 18, while the coarser material passes over the backfall into the re-circulating trough 3 for further and continued treatment. The finer material as produced by the beating action adheres more readily to the roll and as the member 14 is adjusted toward the roll the greater is the amount of coarse material that will pass with the fine material to the take-off member 18;

and vice versa, when the member 14 is adjusted away from the roll 7 less of the coarser material will adhere to the roll to be taken off by the member 18 and more of it will pass over the backfall into the re-circulating trough 3. Accordingly by adjustment of the member 14 the material may be more or less uniformly fine, the member 14 serving to cause the coarser material to remain in the beater unit until reduced to desired fineness.

As indicated in Fig. 1 the pulp or stock may be operated upon successively by a series of beating engines, each unit or engine operating upon the stock to reduce it to a predetermined degree of fineness whereupon it is delivered to the next unit where the fineness is reduced to further predetermined degree, and so on in the successive units the degree of fineness is increased until the desired degree of fineness is obtained whereupon it is discharged from the system.

In the example illustrated in Fig. 1 the slides 22 are in the open position, whereby pulp delivered through the trough 19 from the left will drop into the trough 3 of the next unit which will increase its fineness and deliver it through its trough 17 back into the trough 19, if the slide 20 is closed, whereupon the stock will flow through the channel 19 to the next opening 23, drop into the trough 3 of the next unit where it will be reduced further in fineness, and so on throughout the series. The slide 20 may be fully open or partially closed and in the latter case part of the material removed by the member 18 of the unit will pass on to the next unit and part will be re-circulated and further acted upon. Between the openings 23 and 21 of each unit may be provided a removable slide 24 for shutting off the continuity of the trough 19 ensuring that all material delivered by the trough to the opening 23 of a unit must pass into that unit, to be therein operated upon, and then depart to the next unit.

The members 14 of the successive units are adjusted to suitable positions to effect the desired extent of operation upon the stock in the different engine units. For example progressing from left toward the right, Fig. 1, the members 14 may be positioned closer and closer to the successive rolls 7.

The number of units E in the series may be anything suitable or desirable. Ordinarily four to eight units may be employed, though both greater and lesser numbers are contemplated by my invention.

By a system employing a series of units as described, the operation of reducing the stock or pulp to suitable fineness may be considered as a continuous process, in the sense that the material is fed continuously or at suitably short intervals into the first unit of the series and is delivered substantially continuously in suitable degree of fineness from the last unit of the series.

And respecting any single unit, the material is continuously fed thereto and removed therefrom after remaining therein a suitable length of time for reduction to suitable fineness controlled at least in part by the member 14.

What I claim is:

1. A beating engine comprising the combination with a beating roll, of means for withdrawing material from the roll, a channel to which the withdrawn material is delivered, and means controlling delivery from said channel into said engine.
2. A beating engine comprising the combination with a beating roll, of means for withdrawing material directly from the roll, a channel to which the withdrawn material is delivered, and a second beating engine to which said channel delivers the material so withdrawn.
3. A beating engine comprising the combination with a beating roll, means for withdrawing material directly from said roll, a channel to which the withdrawn material is delivered, a second beating engine, and a plurality of means for controlling respectively delivery of material from said channel to said second engine and for returning to said first named engine the material withdrawn from said roll.
4. A beating system comprising a plurality of beating engines, a channel common to said engines, means for withdrawing material directly from the roll of each of said engines and delivering it to said channel, and means for delivering material from said channel to the next engine in the series.
5. A beating engine for the preparation of pulp, comprising a beater roll, a backfall, and means carried by said backfall and adjustable toward and from said beater roll for increasing and decreasing, respectively, the amount of material that adheres thereto as rotation of the roll continues beyond said backfall.
6. A beating system comprising a plurality of beating engines, a channel common to said engines, a beater roll for an engine, and a screenless member co-operating with said beater roll for determining the characteristics of the material that circulates in said channel.
7. A beating engine comprising the combination with a beater roll, backfall and circulating channel, of a pivoted member comprising in effect a movable extension of said backfall, and means to vary the position of the upper end of said member to change the angular relation between said extension and the surface of said roll.

CHARLES H. KIRCOAF.
